Filed May 5, 1965, Ser. No. 85,125

Term of patent 14 years

(Cl. D32—1)

FIG. 1.

FIG. 2.

FIG. 3.

FIGURE 1 is a side elevational view of a combustion supporting kindling showing my new design, in folded condition;

FIGURE 2 is a front elevational view thereof; and,

FIGURE 3 is a top plan view but showing the same in unfolded condition and with a portion broken away to show internal structure.

The side, rear and bottom not shown are respectively substantially a mirror image of the side, front and top of the design shown.

I claim:

The ornamental design for the combustion supporting kindling, as shown and described.
